ALIGNING MEANS FOR BELT CONVEYERS

James Thomson, Glasgow, Scotland, assignor to
Mavor & Coulson, Limited, Glasgow, ScotlandApplication May 6, 1947, Serial No. 746,375
In Great Britain April 16, 1945

6 Claims. (Cl. 198—202)

1

This invention refers to conveyors of the endless belt type, in which at least one run of the belt is carried by a series of idler rollers incorporated in training, or self-aligning, units supported by swivel mountings.

The invention is especially, although not exclusively, applicable to conveyors of the type stated in which the conveying run of the belt is troughed transversely by the use of inclined idler rollers on which the belt is carried. A usual arrangement is for the idler rollers to be grouped in sets of three rollers, each set comprising a horizontal central roller and an inclined outer roller at each side end-to-end with the central roller. There may of course be other numbers of rollers in a set to give the desired trough effect. The main object of this invention is to provide an improved construction of belt-correcting means, the purpose of which is to return the belt to centralised running in the event that it should deviate to one or other side and which acts, in case of need, in two belt-correction stages, namely—a first stage action in which a minor corrective is applied to the belt when riding slightly out of centre; a second stage action in which a major corrective, almost positive in its effect, is applied to the belt side.

Another object is to effect a first-stage belt-correcting action by adding a light but definite frictional drag to the belt at one side, by means of a normally inactive contact roller and, if necessary, to effect a second-stage belt-correcting action by applying a grip to the belt side by means of the contact roller, in which event the belt tugs the unit to swivel on its mounting.

The desired belt-centering function of the contact rollers can be got by placing them to act on the belt in a plane that is perpendicular to the belt and contains the idler-roller axis or axes. A contact device so placed exercises the same relationship to the belt in both directions of running.

Training idler units as above described are located at intervals in the length of the conveyor, the other idler sets being as usual of fixed construction and requiring no adjustment for reversal of the conveyor.

An example of training units according to the invention, as applied to a conveyor of the type stated, will now be described with reference to the accompanying drawings, in which:

Fig. 1 is an elevation of an upper belt-troughing unit and a lower return-run unit, and Fig. 2 is a side elevation of the units. Fig. 3 is a plan of the upper unit. Fig. 4 is a section on the line

2

IV—IV of Fig. 3, being drawn to a larger scale. Fig. 5 is a plan of a lower component of the base of either unit, on which base the idler brackets are mounted; and Fig. 6 is a section on the line VI—VI of Fig. 5 but showing upper and lower components of the base.

With reference firstly to the upper belt-troughing unit, this includes three belt-troughing idler rollers 7, 8 and 9, which are journaled on brackets 10 secured to an upper base plate 11 which is swivel-mounted on a lower base plate 12 secured to the conveyor frame structure 13 (Fig. 1). Each idler roller is borne by ball-bearings, one set of such bearings being shown at 10A in Fig. 4. The swivel-mounting is such that the rollers 7 to 9 and the base plate 11 are free to swivel as a unit to a small extent about a vertical axis at the centre line of the conveyor. The swivel-mounting comprises a ball bearing 14 interposed between the two components 11 and 12 of the base. At each end of the upper base plate 11 a bracket 15 extends upwards past the outer end of the adjacent side roller 7 or 9 and carries the contact device.

25 In the example, the contact device comprises a small outside roller 16 which is in transverse alignment with the rollers 7, 8 and 9, and whose axis is slightly inclined to the axis of the adjacent roller 7 or 9, and which extends inwards from the bracket 15 towards the outer end of the inclined roller. The contact roller 16 comprises a first part 16A, which is of the same size as each roller 7 and 9 and the inner end of which nearly touches the outer end of the adjacent side roller, and an enlarged flange-like second part 16B

30 located at the outer end of the first part and of larger diameter. The inner face of this second part has a number of rounded projections 17 on it. Each contact roller 16 is borne by a hollow journal 16C welded to the bracket 15, the arrangement being such that the diametral size of the relatively sliding surfaces of the roller 16 and journal 16C is as large as practicable in proportion to the diametral size of the roller portion 16A, so that said surfaces impose on the roller a frictional drag which renders the roller noticeably resistant to rotation in comparison with the inclined idler rollers 7 and 9 on their antifrictional ball-bearings.

35 In use of the unit, if the belt 18 runs to one side it rides on to the slightly upwardly inclined part 16A of the contact roller. Ordinarily, the frictional resistance to rotation offered by the roller 16 should be sufficient to induce the unit to swivel on the lower base plate 12 into a belt-

centering position such that the sidewise displaced belt is trained or steered back to its central path in relation to the conveyor structure 13. If, however, the sidewise displacement of the belt continues, its edge eventually comes in contact with the projections 17 on the second part, which serves as a side limit-stop, so that the unit is forced to swivel sufficiently to train or steer the belt back to its central path.

The extent to which the upper belt-troughing unit can swivel is limited by pins 19 which extend into slots, one of which is shown in Fig. 5, being denoted by 20. The upper plate 11 is maintained central in relation to the lower plate 12 by the body of a central pin 21 screwed into the upper plate 11. Lubricant is supplied by conduits 22 to the race of the ball bearing 14. A lubricant-retaining ring 23 is interposed between the plates 11 and 12, said ring closely surrounding the usual cage-ring 24. The ring 23 performs the additional function of preventing dirt from passing into the ball bearing 14. When lubricant is forced into the bearing, some of it squeezes outwards between the ring 23 and the base components 11 and 12, thus forming a seal and also carrying away from the proximity of the ring 23 any dirt which might have reached there.

As will be seen best in Figs. 2 and 3, if the belt 18 (not shown in Fig. 3) should be displaced sideways from its central setting, the contact rollers will act on the belt at points along a transverse plane which is indicated by the line P—P in Fig. 2 and of which the right-hand portion is represented by the section-line IV—IV in Fig. 3, said plane being perpendicular to the belt and the axes of the idler rollers 7, 8 and 9 being contained in said plane. It is by virtue of this arrangement that the contact rollers exercise their centralising function irrespectively of the direction in which the belt is travelling for the time being.

Modifications may be made without departing from the scope of the invention. For instance, instead of having contact rollers slightly inclined to the inclined troughing rollers 7 and 9, each contact roller may be coaxial with the adjacent troughing roller and may have its inner portion 16A made with a slight outwardly divergent taper.

In the foregoing description with reference to the drawings, the invention has been described only as applied to the upper unit which comprises the troughing idler rollers 7, 8 and 9 that support the conveying run of the belt 18. The invention is also applicable to units having rollers which support a flat conveyor, typical units of this kind being used in the conveyor herein described by way of example as applied to the lower return run of the belt 18. A lower unit is shown in Figs. 1 and 2.

Referring to Figs. 1 and 2, the lower run of the conveyor is denoted by 18A. As shown, the lower unit comprises a single horizontal idler roller 25 which supports the lower run 18A, maintaining the belt in flat form. The roller 25 is associated at opposite ends with contactor rollers 26 each of which has the same construction as, and is mounted on large-surface bearings similarly to, each of the contactor rollers 16 of the upper units. The contact rollers 26 are arranged coaxial to the belt-supporting roller 25, the axle 27 of which is journaled in brackets 28 on the upper plate 29 of a base including also a lower plate 30 secured to the stationary side structure 31 of the conveyor. The construction and arrangement of the upper and lower base plates

29 and 30 is similar to that of the plates 11 and 12 of the upper units and the means provided for lubrication and sealing are also similar.

In the event that the return run 18A of the conveyor should become displaced towards one side, it at first contacts the top surface of the contactor roller 26 at that side, the frictional drag of the contacted rollers tending to swivel the rollers 25 and 26 and the plate 29 as a unit 10 on the stationary base plate 30 and thus to impart a centralising action to the return run 18A. If the belt continues to become displaced further sideways, it eventually engages the enlarged flangewise outer part of the roller 26, said part 15 acting as a limit stop to the sidewise motion of the belt and ensuring that the requisite swivelling motion of the unit 25, 26, 29 takes place.

It will be manifest that the surfaces of the rollers 26 contacted by the belt lie at points in 20 a transverse plane Q—Q which contains the axis of the roller 25 and which is perpendicular to the lower run 18A of the belt. Thus, the belt centralising action takes place irrespectively of the direction in which the belt is travelling for 25 the time being.

It will be manifest that the invention provides a self-aligning endless-belt idler unit comprising 30 one or more anti-friction rollers 25 or 7, 8 and 9 and supported by an anti-friction swivel mounting 29, 30 or 11, 12, with belt-correcting end roller assemblies each comprising a bearing 16C, a contact roller 16 journaled on said bearing in sliding frictional engagement therewith, the contact roller 16 being arranged beyond an end of 35 the unit so that in normal central running of the endless belt the contact roller is stationary, being clear of the belt 18, a roller surface 16A on the contact roller which surface is contacted by the underside of the belt 18 only if the belt rides 40 sideways, and which inclines upwards relative to the underside of the belt so as to be all the better engaged thereby, and an outer enlargement 16B on the contact roller having rounded projections 45 17 to engage the upperside of the belt if the belt rides excessively sideways, so that the belt is gripped between said surface and projections and in effect imparts a succession of corrective tugs to the unit. That is to say, whenever the belt 50 is fully displaced sideways, its side is gripped between the surface 16A of the now rotating contact roller 16 and that projection 17 which, for the time being, is passing through the topmost position in which a projection 17 is shown in Fig. 4. In the continued rotation of the contact roller 55 16, the active projection 17 as it follows its circular path must press deeper into the nearly straight belt side. Thus, because of the action of the projection 17, the belt will tug the entire unit to swivel about its axis (pin 21).

60 I claim:

1. In a self-aligning endless-belt idler unit which in use is supported by a swivel mounting, a belt-correcting end roller assembly comprising a bearing supported on said unit, a contact roller 65 journaled on said bearing in frictional engagement therewith, said contact roller being arranged beyond an end of said unit so that in normal central running of the endless belt the contact roller rests stationary beyond the belt, 70 a roller surface on said contact roller which surface is contacted by the underside of the belt only if the belt rides sideways, and an outer enlargement on said contact roller having projecting means to engage the upperside of the belt 75 if the belt rides excessively sideways, so that the

belt is gripped between said surface and projecting means.

2. In a self-aligning endless-belt idler unit which comprises a support and several anti-friction rollers arranged thereon to form a conveyor belt into trough formation and which in use is supported by an anti-friction swivel mounting, said rollers including two outer rollers each set at an inclination, a belt-correcting end roller assembly at each end of said unit, each assembly comprising a bearing which is mounted on said support and the axis of which is in the same transverse plane as the axes of said outer rollers, a contact roller journalled on said bearing in sliding frictional engagement therewith, said contact roller being arranged beyond an adjacent one of said outer rollers so that in normal central running of the trough-formed belt the contact roller rests stationary beyond the belt, a roller surface on said contact roller which surface is contacted by the underside of the belt only if the belt rides sidewise and which inclines upwards relative to the active surface of said adjacent outer roller and an outer enlargement on said contact roller having rounded projections to engage the upperside of the belt if the belt rides excessively sidewise, so that the belt is gripped between said roller surface and projections.

3. In a self-aligning endless-belt idler unit which comprises a support and several rollers arranged thereon to form a conveyor belt into trough formation and which in use is supported by a swivel mounting, said rollers including two outer rollers each set at an inclination, a belt-correcting end roller assembly at each end of said unit, each assembly comprising a bearing which is mounted on said support and the axis of which is in the same transverse plane as the axes of said outer rollers, a contact roller journalled on said bearing in frictional engagement therewith, said contact roller being arranged beyond an adjacent one of said outer rollers so that in normal central running of the trough-formed belt the contact roller rests stationary beyond the belt, a roller surface on said contact roller which surface is contacted by the underside of the belt only if the belt rides sidewise, and an outer enlargement on said contact roller having projecting means to engage the upperside of the belt if the belt rides excessively sidewise, so that the belt is gripped between said roller surface and projecting means.

4. In a self-aligning endless-belt idler unit which comprises a support and an anti-friction idler roller thereon and which in use is supported by an anti-friction swivel mounting, a belt-correcting end roller assembly at each end of said unit, each assembly comprising a bearing which is mounted on said support and the axis of which is in the same transverse plane as the axis of said idler roller, a contact roller journalled on said bearing in sliding frictional engagement therewith, said contact roller being arranged beyond an end of said idler roller so

that in normal central running of the endless belt the contact roller rests stationary beyond the belt, a roller surface on said contact roller which surface is contacted by the underside of the belt only if the belt rides sidewise and which inclines upwards relative to the active surface of said idler roller, and an outer enlargement on said contact roller having rounded projections to engage the upper side of the belt if the belt rides excessively sidewise, so that the belt is gripped between said roller surface and projections.

5. In a self-aligning endless-belt idler unit which comprises a support and an idler roller thereon and which in use is supported by a swivel mounting, a belt-correcting end roller assembly at each end of said unit, each assembly comprising a bearing which is mounted on said support and the axis of which is in the same transverse plane as the axis of said idler roller, a contact roller journalled on said bearing in frictional engagement therewith, said contact roller being arranged beyond an end of said idler roller so that in normal central running of the endless belt the contact roller rests stationary beyond the belt, a roller surface on said contact roller which surface is contacted by the underside of the belt only if the belt rides sidewise, and an outer enlargement on said contact roller having projecting means to engage the upperside of the belt if the belt rides excessively sidewise, so that the belt is gripped between said roller surface and projecting means.

6. In a self-aligning endless-belt idler unit, including an anti-friction roller and a support by which the roller is carried and which in use is supported by an anti-friction swivel mounting, a belt-correcting end roller assembly comprising a bearing mounted on said support and arranged beyond an end of said anti-friction roller, a contact roller journalled on said bearing in sliding frictional engagement therewith so that in normal central running of the endless belt the contact roller rests stationary beyond the belt, a roller surface on said contact roller which surface is contacted by the underside of the belt only if the belt rides sidewise and which inclines upwards relative to said underside, and an outer enlargement on said contact roller having rounded projections to engage the upperside of the belt if the belt rides excessively sidewise so that the belt is gripped between said roller surface and projections.
